UNITED STATES PATENT OFFICE.

EDMUND B. HAYWOOD, OF RALEIGH, NORTH CAROLINA.

KNIFE-SHARPENER.

1,131,374.

Specification of Letters Patent.

Patented Mar. 9, 1915.

Application filed August 12, 1913, Serial No. 784,443. Renewed August 3, 1914. Serial No. 854,850.

To all whom it may concern:

Be it known that I, EDMUND B. HAYWOOD, a citizen of the United States, residing at Raleigh, in the county of Wake, State of North Carolina, have invented certain new and useful Improvements in Knife-Sharpener; and I do hereby declare the following to be a full, clear, and exact description of the invention, such as will enable others skilled in the art to which it appertains to make and use the same.

This invention relates to improvements in cutlery and edge tool sharpening devices, and particularly to an improvement on my copending application for knife sharpener, filed April 4, 1913, Serial Number 758,869.

One object of the invention is to provide a simple device of this character through which a knife blade may be drawn to effect 20 sharpen the same and in which pressure on the knife blade can be increased or diminished at will.

Another object is to provide a device of this character in which the abrading elements may be adjusted toward and away 25 from each other.

Other objects and advantages will be apparent from the following description, when taken in connection with the accompanying 30 drawings.

In the drawings: Figure 1 is a side elevation of the sharpener. Fig. 2 is a front elevation. Fig. 3 is a top plan view. Fig. 4 is a vertical transverse section on the line 35 4—4 of Fig. 3. Fig. 5 is a vertical longitudinal section on the line 5—5 of Fig. 3. Fig. 6 is a section, similar to Fig. 4, showing a knife in position therebetween.

Referring particularly to the accompanying drawings, 10 and 11 represent respectively the lower and upper blocks, these blocks being of suitable thickness and preferably rectangular in plan view. To the under face of the upper block 11 are secured 45 the abrading elements 12, these elements being of any suitable material, as metal files, or stones. These abrading elements are secured in grooves 13 extending transversely of the under face of the block 11, and are 50 arranged in suitably spaced parallel relation. Similar abrading elements 14 are secured in grooves 15 in the upper face of the lower block 10, and are in parallel relation with each other, but in staggered relation to 55 the elements of the block 11. The block 10

is formed with perforated ears 16 through which suitable fastening devices may be passed to attach the device to a support. Secured to the under face of the block 10, and adjacent the rear edge thereof is one end of 60 a bow spring 17, the opposite end of said spring being bent under itself and secured to the upper face of the block 11. The spring 17 permits the blocks 10 and 11 to be 65 yieldably adjusted toward and away from each other and pressure on the knife to be regulated. The spring also permits the inner end of the block 11 to move vertically.

Formed through the doubled portion of the spring is an opening 19 through which 70 passes the shank of a bolt 20, the inner end having a squared portion 21 and a head 22, said squared portion being formed inwardly of the head. The opposite end of the bolt is threaded and passes through the before- 75 mentioned opening 19, a winged nut 23 being carried thereby and arranged to bear against the outer face of the curved portion 18. The squared portion 21 is fitted snugly within a square opening 24 formed centrally 80 in a double-winged member 25, this member being disposed vertically within the doubled portion of the spring 17 and bearing with its ends against the upper and lower portions of the spring. By manipulating the winged 85 nut 23 the member 25 can be forced inwardly or outwardly so that its wings will force the portions of the spring 17 apart, or permit them to contract, thus accomplishing the adjustment of the blocks 10 and 11 toward and 90 away from each other.

In using the device, the knife blade is inserted between the free ends of the blocks and pressure applied on the upper block. The knife is then moved longitudinally between the blocks, the abrading elements beveling both sides of the edge of the knife at the same time. With the device it is only necessary to pass the knife back and forth between the blocks several times to produce 100 a keen edge. By means of the member 25 the blocks can be moved toward and away from each other to permit the knife blade to be presented to new portions of the abrading elements.

105

What is claimed is:—

A knife sharpening device comprising a pair of blocks, the opposed faces of the blocks carrying strips of abrasive material, the abrading strips of one block being ar- 110

ranged in staggered relation to those of the other block, a bow spring embracing the blocks and secured at one of its ends to one of the blocks, the other end of the spring being bent under and secured to the other block, a bolt disposed through the doubled portion of the spring, and a double-winged member disposed within the doubled portion of the spring and bearing with its wings

against the spring, said bolt being disposed through the double-winged member.

In testimony whereof, I affix my signature, in the presence of two witnesses.

EDMUND B. HAYWOOD.
